DESIGN FOR AN EARRING

Leopold D. Kline, Kew Gardens, N. Y.

Application February 19, 1948, Serial No. 144,593

Term of patent 14 years

(Cl. D45—9)

To all whom it may concern:

Be it known that I, Leopold D. Kline, a citizen of the United States, and a resident of Kew Gardens, county of Queens, and State of New York, have invented a new, original, and ornamental Design for an Earring, of which the following is a specification, reference being had to the accompanying drawing, forming part thereof.

Fig. 1 is a perspective view of an earring, showing my new design, the earring being in an open position; and

Fig. 2 is a perspective view thereof in a closed position.

I claim:

The ornamental design for an earring, as shown.

LEOPOLD D. KLINE.
